(57) **CLAIM**

The ornamental design for a bending machine, as shown and described.

DESCRIPTION

1. Bending machine

1.1 is a front perspective view of the bending machine;

1.2 is a rear perspective view of the bending machine;

1.3 is a front view of the bending machine;

1.4 is a rear view of the bending machine;

1.5 is a top view of the bending machine;

1.6 is a right-side view of the bending machine; and

1.7 is a left-side view of the bending machine.

The portions of the bending machine shown in broken lines form no part of the claimed design.
